UNITED STATES PATENT OFFICE.

JOSEPH SALOMON, OF CHICAGO, ILLINOIS.

FURNITURE-DISPLAY DEVICE.

SPECIFICATION forming part of Letters Patent No. 783,081, dated February 21, 1905.

Application filed September 14, 1903. Serial No. 173,066.

To all whom it may concern:

Be it known that I, JOSEPH SALOMON, a citizen of the United States of America, and a resident of the city of Chicago, in the county of 5 Cook and State of Illinois, have invented a certain new and useful Improvement in Furniture-Display Devices, of which the following is a specification.

My invention relates to devices for displaying furniture in stores and ware-rooms where it is exhibited for inspection by customers. This class of merchandise is very bulky and takes a large amount of store-room and floor space, and in the case of tables, desks, and the like it has been customary to effect economy 10 in storage and to display the articles at the same time by disposing them in two tiers. In this way one piece has been piled upon another, necessary protection being afforded, but 15 partially and uncertainly, by blocks or strips of wood. The disadvantages of this practice are apparent. The lower article is at all times liable to injury when the upper one is handled above it at arm's length, as must necessarily be done. A heavy weight bearing upon 20 a highly-polished surface even when distributed over a protecting-strip may be injurious to the finish, and the lower article cannot be withdrawn for examination or delivery unless 25 the upper one is lifted bodily from its position.

It is the object of my invention to provide means by which furniture may be stored or displayed in the customary double tiers, but to make each tier independent of the other, 30 to facilitate handling in or out for examination or otherwise, and to do away with the damage which always follows to a greater or less degree upon the handling of heavy pieces 35 of furniture and placing or storing them above and upon each other under the conditions 40 named.

While my invention is of general application and may be used in the support of a variety of articles—such as desks, couches, &c.— 45 I have illustrated and will describe it as applied to the support and display of tables.

A practical embodiment of my invention and a preferred construction thereof is illustrated in the drawings, in which—

50 Figure 1 shows a full elevation of one of

my supports and the upper part of another, a table-top, centrally broken away, being supported between them. Figs. 2, 3, and 4 are respectively side, end, and bottom views of a bail-supporting head adapted to be mounted 55 upon a supporting-column. Fig. 5 is a plan view of the bail, and Fig. 6 is a construction detail of the base by which the standard or column is supported, and Fig. 7 shows certain parts thereof.

Further describing my invention with reference to the drawings, in which like letters and characters of reference denote like parts throughout, A is a tubular column of any convenient or desired height adapted to be held 60 in perpendicular position by the means herein to be described. To the top of the column is secured a head B. This may be a casting or stamping, and the attachment may be made by threading the parts together or by any 65 other suitable expedient. The head B comprises a body portion b, in which is the attaching-opening C. The head is rounded to symmetrical form on the upper side and on the under side may be provided with grooves 70 b'. Below the grooves and projecting outwardly from the corners of the body portion are lugs d, whose upper faces d' are below the bottom of the grooves b' by the thickness 75 of the material in the bail E. This bail may 80 be formed of a continuous wire, so that the greater part thereof makes an elongated oval, while the free ends are offset to form arms e, distant from each other by the length of the body portion of the head B. These arms are 85 then turned substantially parallel to the axis of the oval, so as to make the hinge-pins e'. In the bail so constructed the pins e' fit the grooves b', so as to be seated therein. When turned downwardly, the arms e rest on the 90 upper faces d' of the lugs d and are supported thereby in a horizontal position. This construction makes a readily-removable projecting hinged support which projects far enough from the column to engage the under side of 95 a table-top and which being in the elongated oval form gives a substantial bearing therefor. The head B being symmetrically formed for the engagement or hinging thereto of a bail on either side, as many tables may be 100

supported by a number of the devices as there are supports, less one.

The column A is preferably single and tubular and should present a round section as less liable to injure furniture which may come in contact therewith. It may be held in perpendicular position by the means shown. Two strips of band-iron of suitable width and thickness are bent to form the horizontal part *f*, the feet *g*, the braces *h*, and the bearing ends *i*. The bearing ends may be bolted to the upright standard. The strips should cross each other at right angles beneath the end of the column. At the point of intersection a hole should be made through the two strips. A washer *k*, preferably of thin metal and whose diameter is slightly larger than the internal diameter of the standard A, is placed on the rivet *l*, with a spacing-block *m* therebelow. The rivet is passed through the holes of the foot-pieces at their intersection, and the whole is secured together by riveting at *l'*. A small bolt may be used instead of the rivet, if desired, and is to be considered the equivalent thereof.

When the parts are assembled, the tubular standard A is driven into place over the washer until the lower end comes in contact with the upper of the two strips *f*, so that the parts assume the relative positions shown in Fig. 6. The edges of the washer *k* are thus turned downwardly and conform accurately to the inside diameter of the column. They fit themselves to any variations or irregularities in the interior thereof, and the joint thus formed is riveted and secured against any possibility of side slip on the part of the column.

I have described my invention with reference to a practical and operative embodiment thereof. I do not, however, limit myself to the exact form of construction shown, but claim, and desire to secure by Letters Patent, the following:

1. In a furniture-display device, a support, a head thereon, a bail having two ends seated in sockets in the head, and means on the head for supporting the bail in a horizontal position, substantially as set forth.

2. In a furniture-display device, a support, a head thereon, bearing-points under the head, lugs projecting therefrom, and a bail with arms adapted to rest upon the lugs, and hinge-pins arranged at right angles to said arms to engage the bearing-points, substantially as described.

3. In a furniture-display device, a supporting-column, a head mounted thereon and

formed with open sockets, a bail with free ends adapted to engage the sockets in the head, and means attached to the head to support the bail in a horizontal position, substantially as set forth.

4. In a furniture-display device, a supporting-column, a head mounted thereon, a bail with free ends adapted to engage sockets on the bottom of the head and forming pivotal supports for the bail, and supporting-lugs projecting from the head to support the bail in a horizontal position, substantially as set forth.

5. In a furniture-display device a single tubular supporting-column, a bail with free ends, and a head, said head being centrally attached to the upper part of the column and provided with bearing-notches in its lower side and supporting-lugs extending beyond and lower than said notches for the free ends of the bail, said bail being pivotally engaged in said notches, substantially as set forth.

6. In a furniture-display device, a tubular shaft, a supporting-base, a bolt or rivet passing therethrough, a washer on said bolt or rivet, a spacing-block between the washer and the base, the edges of said washer being adapted to bend over the edges of said spacing-block when inserted in the tubular shaft, substantially as set forth.

7. In a furniture-display device, a tubular shaft, a supporting-base, such base comprising continuous strips of metal with ends secured to opposite sides of the shaft and crossing centrally therebeneath, means for securing said strips together at their crossing, said securing means being continued upwardly into the tubular shaft, substantially as set forth.

8. In a furniture-display device, a tubular shaft, a supporting-base, such base comprising continuous strips of metal with ends secured to opposite sides of the shaft and crossing centrally therebeneath, a bolt or rivet to secure said strips at their crossing, a washer thereon, and a spacing-block between the washer and the base-strips, the edges of said washer being adapted to bend over the spacing-block and conform to the interior of the tubular shaft when the same is placed thereover, substantially as set forth.

In witness whereof I have hereunto set my hand this 11th day of September, A. D. 1903.

JOSEPH SALOMON.
